UNITED STATES PATENT OFFICE.

CHARLES W. YOUNG, OF MILFORD, MASSACHUSETTS.

HAT-SHAPING MACHINE.

SPECIFICATION forming part of Letters Patent No. 656,708, dated August 28, 1900.

Application filed January 16, 1900. Serial No. 1,413. (No model.)

To all whom it may concern:

Be it known that I, CHARLES W. YOUNG, a citizen of the United States, residing at Milford, in the county of Worcester and State of Massachusetts, have invented certain new and useful Improvements in Hat-Pressing Machines; and I do hereby declare the following to be a full, clear, and exact description of the invention, such as will enable others skilled in the art to which it appertains to make and use the same.

The present invention relates to an improvement in hat-pressing machines, and more particularly to a machine for pressing the crowns of hats.

Straw hats are frequently made with fancy-braid brims and plain crowns and women's hats have brims of fanciful shapes, and so in pressing and shaping hats of these kinds it has heretofore been the practice to make the crowns and brims separately, so that the fancy braid of the brim or the fancifully-shaped brim would not be injured in the pressing operation, and after the brim and the crown had been properly shaped and pressed they were sewed together. This method of procedure was necessarily adopted in the manufacture of such hats, while it is desirable that the pressing and shaping operation should follow the making of the complete hat. With the object of simplifying the method of making hats and the avoidance of the shaping of the brims and crowns before they are attached together the present invention contemplates a hat-pressing machine for pressing the crowns of hats without at the same time pressing, shaping, or injuring the brim of the hat, and especially in the manufacture of hats of the kinds above referred to.

I believe that I am the first to produce a hat-pressing machine for pressing the crown of the hat with the brim attached and without pressing or shaping or injuring the brim, and my invention, while it is adapted to the making of various kinds of hats, is especially useful in the manufacture of straw hats of the kinds above referred to.

My invention is not limited to any particular form of machine, but is susceptible of being employed in connection with any desired hat-pressing machine; but in the accompanying drawing I have shown a part of a well-

known straw and felt hat press reorganized in accordance with my invention.

The die-seat 1 is slidingly mounted on the press-rods 2, which support the head 3. The die-seat is raised into its position of pressure, as illustrated, and lowered into its position of clearance by any suitable mechanism, as the pitman 4. The hat-die 5 is interchangeable with other dies to adapt it to the various shapes of hats which it may be desired to press in the machine, being loosely supported in the die-seat in the usual manner. Upon the lower end of the head is mounted the brim-protecting flange 6. The rubber hat-bag 7 is also secured to the lower end of the head and preferably with its edge clamped between the edge of the protecting-flange and the lower end of the head. In the drawing the protecting-flange is shown as secured to the head by means of bolts 8. The crown portion of the hat-bag extends downwardly through the central opening of the protecting-flange into the hat-die, and when expanded by hydraulic pressure applied in the usual manner it presses and shapes the crown of the hat to correspond to the hat-die without affecting the brim. While in some cases where the central part of the protecting-flange projects down into the crown of the hat it may be unnecessary, it is generally desirable to provide this part of the protecting-flange with a flexible washer 9, which is made of strong flexible material, such as leather or rubber reinforced with canvas, which projects down into the crown of the hat and prevents the elastic hat-bag from bursting outwardly between the hat-die and the edge of the protecting-flange.

The operation of my improved hat-pressing machine is as follows: Starting with the hat-die in the position of clearance, the hat is laid in the die and the die is raised into the position of pressure. The hydraulic pressure is then applied to the hat-bag and the crown of the hat is pressed and shaped to fit the hat-die. The brim of the hat, whether of irregular or fanciful shape or of fancy braid, being under the protecting-flange, is not affected by the application of the hydraulic pressure to the hat-bag, but that pressure is exerted only upon the crown of the hat.

Having thus described my invention, I

claim as new and desire to secure by Letters Patent of the United States—

1. In a hat-pressing machine, the combination with a hat-die, of a hydraulic head provided with a hat-bag and a brim-protecting flange, substantially as described.

2. In a hat-pressing machine, the combination with a hat-die, of a hydraulic head provided with a hat-bag and a brim-protecting

flange, said flange having a flexible washer 10 around the opening therein, substantially as described.

In testimony whereof I affix my signature in presence of two witnesses.

CHARLES W. YOUNG.
